Patented Jan. 8, 1918.

UNITED STATES PATENT OFFICE.

JOSEPH PAOLICELLI, OF NEW YORK, N. Y.

BOTTLE-SAFE.

1,252,480.

Specification of Letters Patent.

Patented Jan. 8, 1918.

Application filed July 25, 1916. Serial No. 111,300.

To all whom it may concern:

Be it known that I, JOSEPH PAOLICELLI, a subject of the King of Italy, residing at New York, in the county of New York and State 5 of New York, have invented certain new and useful Improvements in Bottle-Safes, of which the following is a specification.

My invention specifically relates to a milk bottle safe although it is capable of use generally as a means to receive and retain an article against theft or unauthorized removal.

Generally the invention aims to provide a novel and improved construction to attain 5 the end in view and one particularly having a lock bolt member coöperating with a locking member being movable to release the locking member, and to provide such a device having a supporting plate with one or 0 more slots or openings to retain the article, a pivoted locking member to close the slot or opening, a spring-controlled slidable lock bolt having a head with which the arms fasten against outward movement, and a 5 latch means for the lock bolt member.

With the above and additional objects, such as will hereinafter appear, in view, the invention has been embodied in one preferred form as illustrated in accompanying 0 drawings wherein:—

Figure 1 is a view showing the safe connected to a support, the safe being partly in section and taken substantially along the lines 1—1 of Fig. 3;

5 Fig. 2 is a front elevation having one of the locking members closed and another opened;

Fig. 3 is a view showing my improvements on an enlarged scale in plan, and partly 0 broken away to show details;

Fig. 4 is a detail perspective view of the spring which may be used to secure the locking member in closed position, and

Fig. 5 is a cross sectional view on the line 5 5—5 of Fig. 3.

Referring specifically to the drawings, wherein like reference characters designate like or similar parts, a conventional form of support for the improved safe is shown 0 at A and which may be a wall, door or other suitable structure. My improvements are mounted from the support A by means of a lock bolt which is designated 6 and which is preferably square or polygonal in cross 5 section so as to prevent a tendency to turn in the support. Exteriortly of the support, a housing is provided which may have a vertical wall 7 through which the lock bolt 6 slides and by means of which the housing is secured to the support A through the 60 medium of screws or other fastening means 8 as well as by the lock bolt. The housing or base proper has an upper wall 9 and a lower wall 10, parallel with the wall 9 and spaced from the other by means of the wall 65 7 with which they are integral. The lower wall 10 serves as a supporting wall and to this end is provided with any desired number of suitably shaped openings or slots 11, open at one end, and adapted to receive milk 70 bottles or other articles 12, having the usual bead or enlargement 13 at the mouth adapted to rest directly on the wall 10 at the openings. The wall 9 serves as a shield for the bottle or articles 12, at their mouths. 75

A substantially rectangular head or plate 14 is formed integral with the bolt 6 at the front end and is provided with a plurality of slots 15 which receive portions 16 of the plates 9 and 10 provided by cutting the plates 9 and 10 away to form the slots at 17. This head 14 in closed position receives the said portions 16 and thus the bolt is braced and guided in its movement and the walls 9 and 10 are braced 80 against relative movement. A coil spring 18 surrounds the bolt in the housing and abuts the wall 7 and also the head 14, thus serving to normally urge the bolt outwardly and the head 14 to the dotted line position 90 suggested in Fig. 3. A suitable means is provided to normally maintain the bolt 6 in retracted position such as that illustrated in the drawings. This means may be a latch having a plate 19 fastened to the interior of 95 the support A in any suitable manner and preferably having an opening 20 through which the bolt 6 extends and is guided. A housing 21 extends from the plate and mounts the latch bolt 22 which is urged outwardly from the housing by means of an expansion spring 24 and which is retracted by manipulation of a knob 25 connected to the latch bolt. The latch bolt 22 extends into a suitably shaped notch 26 provided on 100 the bolt 6. Outward movement of the bolt is limited by the provision of a suitable abutment, which may be a cotter-pin 27 connected to the bolt adjacent its outer end. At its said outer end, the bolt 6 is beveled, 110

for instance at 28 so that it may coöperate with the outer beveled wall of said bolt 22 in retracting the bolt 6 in order to freely pass the bolt 22.

5 The articles 12 are fastened in place by means of locking bars or members 29 which swing intermediate the plates 9 and 10 from vertically disposed pivots 30 mounted by the plates. At the locking ends of the bars 29, suitable locking members are provided which have laterally extending portions 31 and portions 32 extending therefrom toward the bars and at an angle to the portions 31. These portions 32 are spring leaves and are 15 adapted to yield when they pass the sides of the plate 14 in moving to closed position, and to yield outwardly after they pass the plate 14 so that their free ends will abut the plate 14 and prevent opening of the bars or 20 members 29. The bar 29 to the left in Fig. 3 is shown as open while the bar to the right in the same figure is shown as closed and particularly illustrates the locking of the portion 31 with the plate 14. If de- 25 sired, the outer ends of the bars 29 where the pivots 30 pass therethrough may be enlarged as at 33.

In use, the bolt 6 is in retracted or set position and held in such position against the 30 tension of spring 18 by means of the latch bolt 22. With a bar 29 unlocked, as at the left in Fig. 3, a bottle 12 or other article is inserted into the opening 11 so that its enlargement at 13 will rest upon the wall 10 35 as a shelf or support. Afterward, the bar is moved inwardly so that the leaf 32 will pass the plate 14 and then open or clip into engagement with the inner wall of the plate 14, or in other words be in the position 40 shown at the right of Fig. 3. As a result, the bottle or other article will be fastened against removal by an unauthorized person and in addition it will be protected at the mouth by the shield wall 9.

45 If an authorized person wishes to remove the bottle or article 12, knob 25 is manipulated, so as to retract the bolt 22 and release the bolt 6 whereupon the spring 18 expands and throws the bolt 6 outwardly into the 50 position suggested by dotted lines in Fig. 3. As a result the arms 29 are freed and are capable of being manually moved outwardly prior to manually removing the bottle or other article outwardly from the openings

55 11. It will be understood, that prior to again placing articles in the device, the bolt 6 is retracted by simply pressing the head 14 inwardly which causes the bolt 6 due to the bevel 28, to move the bolt 22 inwardly 60 and maintain it in such position until it comes into registry with the notch 26 when it is urged outwardly by the spring 24.

It will be realized that the invention provides a means whereby the milk man in the 65 mornings or at the proper time for delivery

may place the milk bottle or bottles in the safe and then close the bars 29 and that the bottles will thus be maintained in the safe and protected against theft or unauthorized removal, until the owner releases the bolt 6 70 from the interior of the house or support by manipulation of the knob 25.

Since merely the preferred embodiment of the invention has been illustrated and described, it is to be understood that changes 75 in the details of construction, combination and arrangement of the parts may be resorted to without departing from the spirit and scope of the invention.

I claim:—

1. A safe of the class described having a supporting wall provided with an article receiving opening, a shield wall disposed adjacent said opening, means for connecting said walls, a locking bar pivoted on said supporting wall to close said opening, said bar having a locking member provided with a yieldable leaf, a sliding member mounted in said connecting means said sliding member having a head provided with slots, said supporting wall being provided with portions entering said slots, said leaf abutting the head from the interior at times, means for normally forcing the slidable member in one direction, means for preventing movement of the slidable member, and means for limiting the sliding movement of the slidable member when released from the last mentioned means. 90

2. A safe of the class described having a 10 supporting wall provided with a pair of article receiving openings, a shield wall disposed above said openings, a connecting wall for said walls, locking bars pivotally mounted between the first mentioned and second mentioned walls, a sliding bolt mounted between said first mentioned walls, and movable through said connecting wall, said bolt being positioned between the openings of the supporting wall, a head mounted 11 upon one end of said sliding bolt, means for normally retaining said sliding bolt in one position, said locking bars having locking spring members on their free ends for engagement with said bolt when the latter is 12 in normal position and means for forcing said locking bolt in one direction when released.

3. A safe of the class described having a supporting wall provided with an article-receiving opening, a shield wall disposed over said opening, a connecting wall for said walls, a pivot member mounted by said supporting walls, a locking bar mounted on said pivot member to close said opening, said bar having a locking spring thereon provided with a yieldable leaf, a bolt slidable through said connecting wall, said bolt having a head provided with slots, said supporting wall being cut away to provide portions en- 13

tering said slots, said leaf when the bar is in closed position abutting the head from the interior, an expansion spring surrounding said bolt and abutting said connecting wall and said head, a latch engageable with the bolt to maintain it in retracted position, means on the bolt to limit its projecting movement, and said bolt having a

beveled portion to facilitate initial engagement of the latch upon retraction. 10

In testimony whereof I affix my signature in presence of two witnesses.

JOSEPH PAOLICELLI.
